COOKING VESSEL

Joan Stevens, New York, N.Y., assignor to Lincoln Metal Products Corporation, Brooklyn, N.Y., a corporation of New York

Filed Jan. 15, 1970, Ser. No. 20,933

Term of patent 14 years

Int. Cl. D7—02

U.S. Cl. D44—1

FIG. 1.

FIG. 2.

FIG. 4.

FIG. 3.

FIG. 1 is an elevational view of a cooking vessel showing my new design;

FIG. 2 is a top plan view thereof;

FIG. 3 is a side elevational view thereof; and

FIG. 4 is a bottom plan view thereof, with a portion broken away for convenience of illustration.

I claim:

The ornamental design for a cooking vessel, substantially as shown and described.
